CLAIM

We claim the ornamental design for a racquet equipment bag, as shown and described.

DESCRIPTION

FIG. 1 is a top, side perspective view of a racquet equipment bag;

FIG. 2 is a top, second end perspective view of the portion of the racquet equipment bag of FIG. 1;

FIG. 3 is a first side view of the portion of the racquet equipment bag of FIG. 1;

FIG. 4 is a second side view of the portion of the racquet equipment bag of FIG. 1;

FIG. 5 is a first end view of the portion of the racquet equipment bag of FIG. 1;

FIG. 6 is a second end view of the portion of the racquet equipment bag of FIG. 1;

FIG. 7 is a top view of the portion of the racquet equipment bag of FIG. 1; and,

FIG. 8 is a bottom view of the portion of the racquet equipment bag of FIG. 1.

The ornamental design that is claimed is shown in solid lines in the drawings. The broken (dashed) lines shown in FIGS. 1 through 8 are included for the purpose of illustrating environmental elements only and form no part of the claimed design. The broken (dashed) lines shown in FIGS. 1 through 8 are not intended to illustrate or represent stitching or any other non-environmental elements.
